UNITED STATES PATENT OFFICE.

EDWIN WHITSON, OF WOODSTOCK, ILLINOIS.

LOCKING DEVICE FOR MILK-CANS.

SPECIFICATION forming part of Letters Patent No. 339,829, dated April 13, 1886.

Application filed August 18, 1885. Serial No. 174,706. (No model.)

To all whom it may concern:

Be it known that I, EDWIN WHITSON, of Woodstock, county of McHenry, and State of Illinois, have invented certain new and useful

5 Improvements in Locking Devices for Milk-Cans, of which the following is a full, clear, and exact description, that will enable others to make and use the same, reference being had to the accompanying drawings, forming a part 10 of this specification.

This invention relates to means for securing the cover on milk-cans; and it consists in certain novel features in the construction, arrangement, and combination of parts, as will 15 be hereinafter set forth, and pointed out in the claims.

Figure 1 is a sectional view of a milk-can embodying my improved features; Fig. 2, a perspective of the lug D, and Fig. 3 shows the 20 cover removed from the top of the can and held in a suspended position on the side.

Referring to the drawings, A represents the milk-can, B the neck, and C the removable cover. The inner flattened perforated 25 end of the curved lug D is riveted or otherwise rigidly secured to the cover C, as shown in Fig. 1. The outer projecting end of this lug is provided with the opening a, through which the upper bifurcated end of the bracket E projects when the can is closed. The lower end of the bracket E is rigidly secured to the outside of the neck of the can. The cam end a' of the locking-lever F is pivoted in the upper end of the bracket E, and has a bearing in the concavity a² of the lug or ear D, thus having a clamping or wedging function when locking the cover in a closing position. The opposite convex surface, a³, of the lug D bears against the rim a⁴ at the same 40 time, as shown in Fig. 1. The opposite end of the locking-lever F terminates in the enlarged coiled end d, which serves to retain the cover in a suspended position at one side of the can when the same is uncovered, as shown 45 in Fig. 3, thus preventing the cover from being separated and lost. When the can is closed and the cover locked in place, the lever F is in the position shown in Fig. 1. Now, to remove the cover, raise the locking-lever up 50 to the position indicated by the dotted lines, when the cover may be raised, the lug D

clearing the upper end of the bracket E and passing down on the lever F to the opposite position shown in Fig. 3, and retaining the cover in position for immediate use.

55

Cans used in shipping milk are subjected to pretty rough usage, and are often tipped over, and under ordinary circumstances the cover is forced off, spilling a greater part of the contents before the can is restored to its proper 60 position. By this arrangement it will be readily observed that the cover is very securely locked, and cannot be forced off by the tipping over of the can. The second feature—that of retaining the cover so that the same 65 cannot be entirely separated from the can—is also very important, from the fact that the empty cans being returned to the point of shipment are tossed around in a loose manner, and the covers lost or stolen, which causes 70 considerable annoyance and loss.

The locking device will ordinarily be composed of some suitable cast metal, is easily and quickly attached, and adds but little, if any, to the usual cost of the can.

75

Having thus described my invention, what I claim, and desire to secure by Letters Patent, is—

1. In a locking device for milk-cans, the combination, with the neck B, of the cover C, 80 the lug or ear D, rigidly secured to said cover and provided with the opening a, the bracket E, secured to the neck of the can, and the locking-lever F, pivoted to said bracket, substantially as and for the purpose set forth. 85

2. In a locking device for milk-cans, the combination, with the cover C, of the lug or ear D, having the concavity a² and the convexity a³, the bracket E, and the locking-lever F, provided with the cam end a', whereby 90 said cover is securely locked in a closed position, substantially as set forth.

3. The combination, with a milk-can, of the cover C, the lug or ear D, provided with the opening a, the lever F, having the enlarged 95 or coiled end d, and the bracket E, substantially as and for the purpose set forth.

EDWIN WHITSON.
